UNITED STATES PATENT OFFICE.

MAXIM ZAVARKIN, OF EAST BRIMFIELD, MASSACHUSETTS.

BALLOON.

1,270,678.

Specification of Letters Patent. Patented June 25, 1918.

Application filed March 9, 1918. Serial No. 221,410.

To all whom it may concern:

Be it known that I, MAXIM ZAVARKIN, a citizen of Russia, resident of East Brimfield, county of Hampden, and State of Massachusetts, have invented certain new and useful Improvements in Balloons, of which the following is a specification.

This invention relates to improvements in aeronautic apparatus and has as its special 10 object the provision of a novel form of balloon, comprised of a plurality of independent, inflatable holders and a car carrying mechanism by means of which they are inflated.

15 A further object is to provide a control means whereby the gas holders or tanks may be filled, or emptied in a rapid and convenient manner.

These and other like objects are attained 20 by the novel construction and combination of parts hereinafter described and shown in the accompanying drawings, forming a material part of this disclosure, and in which:—

25 Figure 1 is a side elevational view showing a balloon made in accordance with the invention.

Fig. 2 is a top plan view of the same.

Fig. 3 is a transverse sectional view taken 30 on line 3—3 of Fig. 1, and,

Fig. 4 is a fragmental vertical sectional view taken on line 4—4 of Fig. 1.

Referring to the drawings, the numeral 10, indicates a plurality of independent 35 inflatable gas holders, the same having a segmental cross-section, with curved outer edges, the holders being arranged in close intimate connection one with another, and held by a netting 11, to which is secured the 40 upper end of the support or guy rods 12, the same being extended convergently downward to the circular car 14, which they support.

Contained in the car or basket 14, is a 45 gas tank 16, the same being engaged by a pipe 17, with a hydrogen generator 18, supplying hydrogen gas to the tank, from which it passes through the pipe 20, controlled by the valve 21, to a flexible hose 22, 50 engageable with any of the several downwardly extending tubes 24, connected with the outer row of series of gas holders 10, provided with independent control valves 25.

The inner concave surfaces of the several 55 segmental holders 10, are adapted to make

contact with a central, circular holder 28, also adapted to be inflated by connections with the flexible tube 22, through the pipe 29, controlled by a valve 30, all of the several pipes and valves being of like construction. 60

Secured upon the upper surface of the inner holder 28, is a pair of opposed guides 32 slidably engaging a plate 33, which is adapted to cover an opening 35, leading into the holder 28, or which can be drawn to one side, by reason of eyes 36, secured to the ends of the plate and to which are attached cords 37, the same running over pulleys 38, adjacent to the periphery of the 70 cylindrical holder 28, the cords 37 extending downwardly to the car to which they are attached by other eyes 39, so as to be held against inadvertent dislocation and are arranged convenient to the operator, so that 75 should it be desired to descend, the plate 33, can be drawn endwise, permitting the gas to escape from the central holder.

It is to be understood that the exterior 80 holders 10, when inflated, are so calculated and designed as to support the entire structure including the car, tank, and gas making machine, under normal circumstances, the central holder 28, providing sufficient buoyancy to cause the entire structure to 85 rise into the air and obviously if the slide 33, be removed to one side, so as to permit gas to escape through the opening 35, the balloon will gradually descend.

Having thus described my invention what 90 I claim as new and desire to secure by Letters Patent, is:

1. In a balloon, a plurality of segmental 95 gas holders arranged in a circle, a cylindrical holder adjacent to the inner ends of said segmental holders, a car suspended by said holders, means in said car for supplying gas, flexible connection between said means and said holders, inlets to all of said holders, a slide valve at the upper side of said cylindrical holder and a pair of opposed cords extending from said valve to said car whereby said valve may be manually actuated. 100

2. In a balloon, the combination with a plurality of segmental shaped hollow elements arranged in a circular row, a central cylindrical element against which the inner ends of said segmental elements contact, a car supported by said elements, a gas tank carried in said car, means for supplying gas 110

to said tank, a flexible connection between said tank and said elements whereby they are independently filled with gas, control means on said connection, a sliding plate arranged in the manner of a valve on the upper surface of said cylindrical element, said plate covering an opening extending there-

through, and means for actuating said sliding plate, said means extending downward to said car.

In testimony whereof I have affixed my signature.

MAXIM ZAVARKIN.
